Primary Examiner—Lucy Lieberman(74) *Attorney, Agent, or Firm*—Sughrue Mion, PLLC(57) **CLAIM**

The ornamental design for a wristwatch, as shown and described.

DESCRIPTION

FIG. 1 is a perspective view of the front and right side of a wristwatch showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawing are for illustrative purposes only and form no part of the claimed design.
